United States Patent Office

Des. 215,078
Patented Sept. 2, 1969

215,078

HAT

Stewart Hicks, P.O. Box 15246, Sarasota, Fla. 33778

Filed July 23, 1968, Ser. No. 12,862

Term of patent 14 years

Int. Cl. D2—03

U.S. Cl. D2—248

FIG. 1 is a side elevational view of a hat showing my new design;

FIG. 2 is a front elevational view thereof;

FIG. 3 is a rear elevational view on a reduced scale; and

FIG. 4 is a top perspective view thereof.

I claim:

The ornamental design for a hat, substantially as shown.
